NILS EMIL NILSSON, OF STOCKHOLM, SWEDEN, ASSIGNOR TO TELEFONAKTIEBOLAGET
L. M. ERICSSON, OF STOCKHOLM, SWEDEN, A REGISTERED COMPANY

CALL METERING IN TELEPHONE SYSTEMS

Application filed June 18, 1930, Serial No. 462,104, and in Sweden June 21, 1929.

The present invention relates to a call metering arrangement in telephone systems. More particularly it relates to such telephone systems, in which the talking connections over certain junction lines—by way of example trunk lines connecting different telephone exchanges—are subjected to a special charge, which is registered on the call meter through the intermedium of impulse senders, which are adapted to actuate the call meter in accordance with the tariff in force for the connection in question. Further the invention relates to certain arrangements for transmitting the call meter impulses over the talking connection and for actuating the impulse senders connected to the talking connection, so that said impulse senders may be successively started to send out current impulses to the call meter.

The invention will be more closely described with reference to the accompanying drawing, which shows two impulse senders with appertaining impulse repeating devices, connected to a talking connection in an automatic telephone plant. Each impulse sender with appertaining impulse repeating device forms an impulse sender set, which preferably is common to a plurality of junction lines, and which, when the junction line is used, is automatically connected to the junction line. If desired, each junction line may be provided with such an impulse sender set. The drawing shows only those parts of the talking connection which have anything to do with the impulse metering. In the shown example the call meter impulses are transmitted to the call meter SR over the third wires c_1 , c_2 , c_3 of the talking connection. Said wires include relays R_1 , R_2 , R_3 , R_4 , R_5 , R_6 , which are energized during the call, and of which the relays R_2 and R_4 and R_6 are used for transmitting the call meter impulses. In the shown example it is assumed that the connection is carried over two junction lines which connect exchanges belonging to dif-

ferent tariff zones, and that a special charge is to be registered for each one of these junction lines. Two impulse senders IS_1 and IS_2 with appertaining impulse repeating devices IR_1 and IR_2 are therefore connected to the talking connection. It is assumed in this case that the calls are to be charged for according to a combined zone and time tariff, the arrangement being such, that the impulse sender sets are brought into operation periodically at even intervals of time, by way of example every three minutes. The call metering operation is started by an interrupter PS, disposed, by way of example, at the last selector of the talking connection, which interrupter starts the impulse sender TS_1 by means of a current impulse. Said impulse sender then sends out a number of call meter impulses corresponding to the appertaining junction line, which impulses are transmitted and repeated by the impulse repeating device IR_2 of the other impulse sender set. The impulse sender TS_1 then starts the impulse sender TS_2 , which in turn sends out a number of call meter impulses corresponding to the appertaining junction line, which call meter impulses are transmitted to the call meter. The impulse sender sets shall thus be able to repeat the current impulses sent out from another impulse sender set and shall also be able to start another impulse sender set in such a way, that for each time interval all the impulse sender sets connected to the talking connection are successively brought into operation and send out their series of impulses, which will thus actuate the call meter in such a way, that the sum of the charges for the different junction lines is registered. As the transmission of impulses as well as the starting of the impulse senders must be effected over the same circuits the arrangement according to the invention is such, that the call meter and the impulse sender are actuated by current impulses of different kinds, preferably current impulses of different du-

ration are utilized, the impulse sender being started by means of current impulses of longer duration than the call meter impulses. If desired, the call meter may be adapted to be actuated by both kinds of impulses, in which case the last call meter impulse sent out by one impulse sender at the same time can start the next impulse sender. The drawing shows an embodiment of this kind.

In the embodiment shown on the drawing the impulse sender as well as the appertaining repeating device is formed as an electro-magnetic stepping mechanism provided with rotating cams or the like, which control the sending out of impulses. The impulse sender is driven by means of an electromagnet SM, which through the intermediate medium of a stepping mechanism, which is not shown on the drawing, can impart a step-wise rotating motion to a shaft. A control disc KS and also an impulse disc SS are attached to this shaft. The first mentioned disc is adapted to actuate a contact spring K₁ which connects the driving magnet SM into an impulse circuit as soon as the impulse sender is driven out of its normal position, and which is actuated by the disc KS, so that the impulse sender, after it has been started, is turned a complete revolution. During this motion the impulse disc SS actuates a contact spring K₂, by means of which impulses for actuating the call meter and for starting the next impulse sender are sent out.

The impulse repeating device TR is intended to repeat the call meter impulses and to serve as an intermediate for starting the appertaining impulse sender. For this purpose it is designed as a time relay in such a way, that the impulse sender is started only when the impulse repeating device is actuated by a current impulse of shorter duration than the meter impulses. The impulse repeating device is provided with a driving magnet AM, which by means of an armature SA and a driving pawl DH is rotatably connected to the former and can impart a step-wise rotating motion to a toothed wheel SH. The driving pawl DH is by means of a spring normally held in an inoperative position, but is adapted to be brought into engagement with the teeth of the wheel SH by means of a magnet RM and an appertaining armature RA. The repetition of the impulses is brought about by closing the contact springs K₃, K₄, of which the former is fastened to the armature RA and the latter adapted to co-operate with a cam RS, which is rigidly attached to the same shaft as the wheel SH. The magnets RM and AM are adapted to be connected into circuit simultaneously over normally closed contacts 1 and 2 respectively of the relays R₂ and R₄ respectively. The magnet AM is then connected into a circuit comprising an interrupter PS, the wheel SH being thus made to rotate. The magnet RM

on the other hand remains permanently energized. The contact K₃, K₄ remains closed, however, only until the wheel SH has been moved forward a few steps, as the cam RS is then disengaged from the spring K₄, so that said contact is opened. If the impulse starting the impulse repeating device is of longer duration the magnet AM then continues to move the wheel SH forwards until a pin S, disposed on said wheel, engages and closes contacts 3 and 4 respectively, when the magnet SM of the impulse sender is connected into an impulse circuit including an interrupter PS. The magnet SM then attracts its armature and thereafter receives current over the contact spring K, until the shaft of the impulse sender has rotated one revolution, when the contact spring K₁ interrupts the circuit for the magnet SM. Meanwhile the current impulse, which started the impulse repeating device, has ceased through interruption of the contacts 1 and 2 respectively. When on account of this the magnets RM and AM are deenergized, the wheel SH and the cam RS are through spring action restored to their normal position shown on the drawing.

The switching operation in call metering is as follows. When the talking connection is established the interrupter TS will periodically short-circuit the relay R₂ over the contact 5. This short-circuit is of such a duration, that the impulse sender IS₁ is started thereby. When the relay R₂ on account of the short-circuit drops its armature, the magnets RM and AM of the impulse repeating device are again connected into circuit over the contact 1. The relay R₄ is then initially short-circuited over the contact springs K₃, K₄. Said short-circuit is, however, of such a short duration, that it cannot start the impulse sender IS₂. On the other hand the impulse repeating device IR₂ is actuated by closing the contact 2. The relay R₆ is then short-circuited over the contact springs K₃, K₄ of said impulse repeating device. When on this account the relay R₆ drops its armature the call meter SR receives a current impulse over the contact 6 whereby the first charge is registered. Meanwhile the impulse repeating device TR₁ has continued to operate. As soon as the short-circuit of the relay R₄ at the contact K₃, K₄ is interrupted the impulse repeating device IR₂ is restored to its normal position, which restoration takes place before the impulse sender IS₂ is started. When the pin S on the toothed wheel of the impulse repeating device IR₁ closes the contact 3 the impulse sender IS₁ is started in the above described manner. The contact spring K₂ then short-circuits the relay R₄ a number of times corresponding to the number of teeth on the impulse disc SS. The number of said teeth corresponds to the charge or tariff for the junction line in ques-

tion. In the shown example the impulse sender is provided with 3 teeth, the last of which is so wide, that it brings about a short-circuit of the relay R_4 of long duration and thus starts the impulse sender IS_2 . The first two teeth, on the other hand, generate only impulses of short duration, which in the manner described above are repeated by the impulse repeating device IR_2 and are registered by the call meter SR . The third tooth at first brings about a short-circuit of the relay R_6 of short duration over the contact springs K_3, K_4 and then starts the impulse sender IS_2 , which then in turn sends out a number of impulses corresponding to the junction line in question, in the shown example three impulses, which short-circuit the relay R_6 and are thereby registered by the call meter.

From the above it is clear, that the impulse repeating devices are arranged in such a way, that they at the same time are able to transform the one kind of current impulses to the other kind of current impulses, that means, a current impulse of long duration to a current impulse of short duration. Said arrangement is required to prevent that a current impulse of long duration, at the same time as it is transmitted to the call meter, shall be able simultaneously to start all the impulse senders connected to the talking connection. The impulse of long duration sent out from the interrupter TS is thus transmitted to the call meter SR first after it has been transformed to an impulse of short duration by means of the cam RS of the impulse repeating device, which impulse IR_1 of short duration is then repeated by the repeating device IR_2 but does not start the impulse sender IS_2 .

The starting of an impulse sender can of course also be brought about by means of a special current impulse, which is sent out from another impulse sender first after the call meter impulses have been sent out, and which should therefore not be registered by the call meter. Said starting impulse can also, if desired, be of an entirely different kind than the call meter impulses, by way of example an alternating current impulse, in which case both kinds of current impulses may be transmitted over the same circuits, if arrangements are only made to prevent the call meter from being actuated by the current impulse starting the impulse sender.

I claim:

1. In a switching arrangement for call metering in telephone plants a number of junction lines connecting different tariff zones and provided with impulse senders for sending out to a call meter a number of current impulses corresponding to the charge for the appertaining junction line, and means to actuate said call meter and the im-

pulse senders over the same circuits by means of current impulses of different kinds.

2. In a switching arrangement according to claim 1, means to send out impulses of different kinds in such a way, that said impulse sender after sending out the call meter impulses automatically starts another impulse sender connected to the talking connection.

3. In a switching arrangement for call metering in telephone plants a number of junction lines connecting different tariff zones and provided with impulse senders for sending out to a call meter a number of current impulses corresponding to the charge for the appertaining junction line, means to actuate said call meter and the impulse senders by means of current impulses of two kinds, the call meter being adapted to be actuated by both kinds of impulses while the impulse sender is adapted to be started by only one kind of impulses.

4. In a switching arrangement for call metering in telephone plants a number of junction lines connecting different tariff zones and provided with impulse senders for sending out to a call meter a number of current impulses corresponding to the charge for the appertaining junction line, means to actuate said call meter and the impulse senders by means of current impulses of two kinds, the call meter being adapted to be actuated by both kinds of impulses while the impulse sender is adapted to be started by only one kind of impulses, and means to transform the impulses intended for starting of the impulse sender to a call meter impulse.

5. In a switching arrangement for call metering in telephone plants a number of junction lines connecting different tariff zones and provided with impulse senders for sending out to a call meter a number of current impulses corresponding to the charge for the appertaining junction line, means to actuate said call meter and the impulse senders by means of current impulses of two kinds, the call meter being adapted to be actuated by both kinds of impulses while the impulse sender is adapted to be started by only one kind of impulses and means to transform the impulses intended for starting of the impulse sender to a call meter impulse the former impulses being of a longer duration than the call meter impulses.

6. In a switching arrangement for call metering in telephone plants, a number of junction lines connecting different tariff zones and provided with impulse senders for sending out to a call meter a number of current impulses corresponding to the charge for the appertaining junction line, means to actuate said call meter and the impulse senders by means of current impulses of two kinds, the call meter being adapted to be

actuated by both kinds of impulses while the impulse sender is adapted to be started by only one kind of impulses, and means to transform the impulses intended for starting of the impulse sender to a call meter impulse the former impulses being of a longer duration than the call meter impulses, electromagnetic means adapted to be started by impulses to be transmitted and to repeat said impulses in the form of impulses of short duration independently of the duration of the starting impulse.

In testimony whereof I affix my signature.
NILS EMIL NILSSON.
